UNITED STATES PATENT OFFICE.

HARRY C. ADAM, OF ST. LOUIS, MISSOURI.

LIGHTING FIXTURE.

Application filed August 30, 1920. Serial No. 406,800.

To all whom it may concern:

Be it known that I, HARRY C. ADAM, a citizen of the United States, residing at St. Louis, Missouri, have invented a certain new and useful Improvement in Lighting Fixtures, of which the following is a full, clear, and exact description, such as will enable others skilled in the art to which it appertains to make and use the same.

- 10 This invention relates to lighting fixtures, and has for its object to provide an inexpensive lighting fixture of simple construction and ornamental appearance that will direct the major portion of the horizontal, approximately horizontal, and upwardly-inclined rays from the light source downwardly into the useful plane, and will also softly illuminate the ceiling or space above the fixture.
- 20 To this end I have devised a lighting fixture that consists of suitable metal members with connecting means for attachment to or suspension from the ceiling of a room and a light reflecting and diffusing means formed of translucent glass and consisting of a hollow member comprising three separate parts integrally connected together, namely, a hyperbolic or bell-shaped upper portion open at its upper end and so disposed with relation to the filament of the lighting unit of the fixture that the major portion of the horizontal and approximately horizontal rays will be re-directed into the useful plane by the convexed inner surface of said upper portion, a bottom portion arranged horizontally underneath the lighting unit and an annular band or belt portion of concavo-convex shape in vertical cross section arranged between said upper portion and said bottom portion, and preferably of greater diameter at its widest part than the lower end of the upper portion of said member. Such a lighting fixture is inexpensive to manufacture, due to the fact that the metal parts of same are small and of such design that they can be produced cheaply and the light reflecting and diffusing means consists of a one-piece glass bowl open at its upper end, and another desirable feature of such a fixture is that the light reflecting and diffusing member of same is of such form that all portions of the surface of same will be of substan-

tially the same brilliancy when illuminated, thereby producing a fixture that is of exceptionally attractive appearance.

The figure of the drawing is a view partly in vertical section and partly in elevation of a lighting fixture constructed in accordance with my invention.

Referring to the drawing which illustrates the preferred form of the invention, A designates the light directing and diffusing member of the fixture which is preferably formed of translucent glass and provided with a bottom portion 1 arranged underneath the light source B of the fixture, an upper portion 2 of substantially hyperbolic form or approximately bell shape provided with a convexed inner surface that directs the major portion of the horizontal and approximately horizontal rays which are emitted from the light source downwardly into the useful plane, and an intermediate portion 3 in the form of an annular belt or band of concavo-convex shape in vertical cross section, integrally connected to said bottom portion and upper portion and being of greater diameter than the lower end of said bell-shaped upper portion. The bottom portion 1 of the diffusing member A may be of any preferred shape, but it is essential that said bottom portion be joined to the upper portion 2 by a belt or band of concavo-convex shape in vertical cross section. It is also essential that the upper portion 2 be of substantially hyperbolic form or approximately bell shape and of such length that the lower edge of same terminates at or below the horizontal plane in which the filament α of the light source lies.

The upper end of the member A is open so that it can be passed upwardly over the light source, and when said member is in use the opening at the upper end of same is closed by a member C, preferably formed of light-weight sheet metal and equipped with screws or other suitable devices 3 that cooperate with an annular rib or flange 4 at the upper edge of the member A to sustain said member in operative position.

In the form of my invention herein illustrated the member C is connected to a part D that carries an electrical receptacle 5 in which the lighting unit B is mounted. The

fixture can either be mounted upon or arranged in close proximity to the ceiling of a room, or it can be suspended from the ceiling by a chain or other suitable means.

5 A lighting fixture of the construction above described is exceptionally efficient, due to the fact that the upper portion 2 of the member A is so arranged with relation to the filament of the electric lamp bulb B 10 that the major portion of the horizontal and approximately horizontal rays emitted from the light source will strike the convexed inner side of said portion 2 and be deflected downwardly from same through the bottom 15 portion 1 of the member A. The main portion of the downwardly inclined, oblique rays from the light source pass directly through the bottom portion of the member A and through the concavo-convex band 20 immediately above said bottom portion, and some of the light passes through the upper portion 2 of said member and softly illuminates the ceiling or space above the fixture. It will, of course, be understood that some 25 of the rays are absorbed by the member A, or otherwise lost, but when it is realized that over one-third of all the rays emitted by the light source travel in the paths indicated by the dot and dash lines in the drawing and 30 will be utilized in my fixture to illuminate the space beneath the same, a slight internal loss is of no consequence. Furthermore, the light reflecting and diffusing member is of such form that the rays from the lighting 35 unit strike the different portions of said member at such angles that all portions of

said member will be of practically the same degree of brilliancy, thereby producing a fixture having a luminous member of substantially uniform appearance throughout 40 its entire area.

In order to intercept and utilize light rays above a point where same are directed downwardly by the portion 2 of the member A, a substantially flat reflector E of annular form 45 can be arranged inside of the member A and supported on the neck of the lamp B substantially as shown. This deflector E can be made of any suitable material, preferably metal, such as aluminum or other non-corrosive material, and it is provided with a depending part 6 that surrounds the neck of the lamp so as to maintain the reflector E in proper position.

Having thus described my invention, 55 what I claim as new and desire to secure by Letters Patent, is:

A lighting fixture, comprising an electric lighting unit, and a light reflecting and diffusing member surrounding said lighting 60 unit and composed of a substantially bell-shaped translucent upper portion whose lower end terminates below the horizontal plane in which the filament of the lighting unit lies, a translucent bottom portion arranged under the lighting unit, and a translucent band or belt portion of substantially 65 concavo-convex shape in vertical cross section arranged between said upper and bottom portions and integrally connected to 70 same.

HARRY C. ADAM.
